FRANCOIS CARTIER, OF PARIS, FRANCE

SECRET-TELEGRAPHY SYSTEM

Application filed July 14, 1927, Serial No. 205,711, and in France August 3, 1928.

The object of my present invention is the same as that of my copending application, Serial No. 179,440, filed March 30, 1927, namely, to provide or insure secrecy in coded telegrams transmitted and received with or without wire, by combining the work of keying the signals of a message with an automatic manipulation of "key signals" resulting in a transmission of signals incapable of being utilized and deciphered so as to make up the original signals.

The present invention concerns a mode of construction and arrangement applicable more particularly to Morse apparatus, though it goes without saying that this system is cited solely by way of example, and that the invention is not confined hereto, and that it is applicable to any other transmission and receiving system of the same kind.

Other objects of the invention will be apparent upon reading the following specification in conjunction with the drawings in which,

Figures 1 and 2 show diagrammatically embodiments of my invention;

Figures 3, 4 and 4^a illustrate different forms which the strips may take;

Figures 5 and 5^a illustrate details of my invention; and,

Figure 6 illustrates one form which the driving mechanism may take.

The application of the idea underlying the present invention to Morse-code telegraph apparatus is as follows: Referring to Figure 1, M is an ordinary Morse key whose resting (idle) contact R and whose working contact T are respectively connected with the poles of a battery P₁ through the bars B and A.

m is another key whose contacts (working and idle) are also connected with the poles of the battery P₁. This second key is of the automatic kind, and further below it is shown in what way it is operated. There is further provided an electromagnet E the terminals of which are connected with the axes of the two keys M and m, and whose armature W when in contact with f causes current from a battery P₂ to flow in the line L.

It will be seen that the electromagnet E is only passed by a current when M and m are respectively in the position of rest and in the working position, and vice versa. When m makes contact with its idle contact, the transmissions over line L will exactly correspond to the signals keyed at M. But when m is in engagement with its working contact, the transmission over line L will be complementary relative to the signals keyed at M, in other words, the current of P₂ in L will, as a matter of fact, be broken every time M is depressed, and re-established when M is raised.

Between the rest contact r and the contact c of key m, a tape or band C (Figure 3) known as a "key strip" is caused to travel, said tape being provided with holes along its axis of variable lengths and irregularly spaced apart. The thickness of this strip is so chosen that when c is located opposite a hole, it comes to press upon r and the contact with t is broken, while, on the contrary, when c is on a solid portion of the strip, the contact cr is broken and contact with t restored.

It will be seen that, according whether c is on solid material or located opposite a hole in the tape C, the signals sent out from the line correspond to those keyed at M or are the complements thereof, as has hereinbefore been described.

If the strip C travels during keying, the signals sent into the line L will bear a relationship to those keyed that is entirely irregular and a function of the position of the "key strip". The signals keyed at M are thus converted in the line into other arbitrary signals, series of dots and dashes, which may either correspond in part or not at all to Morse-code signals.

In short, the text keyed in M is automatically coded in the line in accordance with an incoherent law, the period of which is equal to the length of the "key strip".

The same strip can be used for the purpose of obtaining a great number of modifications, for example, by changing its original position at the beginning of each message or series of messages. Also a change

n its speed of travel would result in modifications of the coding.

At the receiving end, equipment similar to that at the sending station is provided (Figure 2). The key *m* is identical to the one at the transmitter station, and it is actuated automatically by a perforated strip which slides between the contact *c* and the back or rest contact *r*, establishing connection of the axis of *m* either with *A* or with *B*.

The key *M* is actuated by an electromagnet *E'* connected with the line *L* and with the ground. The axes of *M* and *m* are connected with the terminals of electromagnet *E* of an ordinary Morse receiver whose armature *W'* prints upon a tape *D* the dots and dashes received by *L*.

It will be seen that if the automatic keys *m* at the transmitter and receiver, or in other words, the key strips, are similarly disposed, the currents passed through *I* will exactly correspond to those keyed at *M*. Hence, the receiver apparatus will thus reassemble automatically the decoded text on the tape *D*.

Interception by an ordinary receiver apparatus of signals sent over the line *L* would not permit of ascertaining the text thereof, unless a key strip identical to the one used for the transmission is available. But even the possession of such a key strip would not save one the trouble of relatively long trials so as to ascertain the starting position of the strip and its traveling speed.

It is necessary to insure absolute synchronism in the travel of the two key strips at the sending and at the receiving ends.

One way of carrying the basic idea of this invention into practice would be in the following manner: The key strip is constituted in a way as shown in Figure 4. In axial sense thereof are formed equi-distant holes just as in a Wheatstone tape, two different keys being mounted upon either side of the axis. Forward feed is insured by a locking or ratchet mechanism actuated in transmission and reception by the electromagnets *E* and *E'* conveniently disposed for this purpose, and there are various arrangements in actual use which are adapted thereto.

The key strip and the key *m* may, for instance, be arranged as diagrammatically indicated in Figure 5. The tape slips over a smooth surface *H* and passes over a groove of a roll *K* whose median section is furnished with studs the distance between which is the same as the distance between the equidistant holes along the axis of the band. The said roll *K* is fixed upon the spindle of a ratchet wheel (not illustrated) which has as many teeth as there are studs upon the roll. A ratchet or locking mechanism controlled by the electromagnet *E* (see Figure 6) causes the said wheel to rotate and thereby also turns the roll *K* a distance equaling the in-

terval between two teeth every time that a current passes through the electromagnet *E*, that is to say, every time either a short or a long signal is sent out or produced by the key *M* and *m* and the key strip.

A diagrammatic view of the said ratchet or locking device is shown by way of example in Figure 6 which also shows the scheme of the electromagnet *E* furnished with a mobile core. When a current flows through the said electromagnet, the core *N* is caused to descend and to be placed longitudinally in the coil. The top end *O* of the pawl carried by a flexible spring slides over the toothed portion of the ratchet wheel *Q* which remains stationary and comes to mesh with the lower tooth. When the current is broken, the core rises again under the action of the spring *U*, and the pawl *O* causes the ratchet wheel *Q* to turn one notch. Stops *S₁* and *S₂* limit the stroke of the core so as to insure precise operation of the ratchet mechanism.

It will be seen (Figure 5) that the key *m* terminates at one side in a wheel *G* provided with a striated portion which is made to press upon the band by the action of a spring *V*. When this wheel is located opposite a perforation of the band, it is slightly lowered. The other end of the key carries a tail piece *F* whose length is fixed by the condition of insuring sufficient amplification of the movements of the wheel *G* so that it passes from contact *r* to the contact *t*. On the other hand, the perforations of the band are of such dimensions that the wheel *G* penetrates sufficiently in the shortest ones thereof so as to occasion a balancing movement as hereinbefore indicated with the key *m*.

In practice, it would be simpler to give, for instance, the key strip a form as shown in Figure 4^a, that is, a Wheatstone strip on which any arbitrary text has been keyed, and it is this text which could be easily used for re-constructing the key strip in case it should have been damaged or destroyed.

In case the thickness of the key band should not be sufficient to directly produce the changes in contact at *t* and *r*, an arrangement as shown in Figure 5^a could be resorted to, which provides for the actuation of key *m* an auxiliary electromagnet *E''* in which a current is produced every time the wheel *G* is located opposite a hole in the band *C* and that it makes contact with *H*.

Every key band constituted as indicated in Figure 4^a gives in reality four keys since it may be used in both directions.

Every derangement or faulty operation of the apparatus would become at once apparent at the receiving end on account of the incoherence of the signals.

It will be evident that by means of a separate switch it would naturally be possible to

cut the secret-coding device out of circuit and to use the apparatus like any ordinary Morse apparatus.

The system here disclosed is useful for any desired keying speed, whether direct or automatic, and it is therefore adaptable particularly to the Wheatstone and similar telegraph systems.

The construction of the electromagnets of course must be adapted to the sensitivity required thereof. For manual operation, ordinary Morse electromagnets will be entirely adequate, while for high-speed transmission, sensitive polarized relays will be used, and the two stops of the armature of the electromagnet E (Figure 1) will be connected, one to the positive pole and the other one to the negative pole, so as to produce in the line, if necessary, alternations of current.

The system could also be applied to radiotelegraphy. In the case of transmission work (Figure 1), all that is necessary is to connect contact *t* with the battery *P₂* by means of an electromagnet intended to produce the signals. For reception (Figure 2), electromagnet E' is actuated by the detector.

Various modifications and different improvements, some of which shall be indicated hereinafter, may be adopted without changing or affecting the spirit of the invention or exceeding the scope thereof.

The key strips could be made from the paper of the tapes used in the Wheatstone telegraph. A band of 100 meters' length would comprise 40,000 equidistant holes arranged axially. Hence, they could form 4 keys of 40,000 intervals furnishing each 40,000 variations or modifications.

Datum points should be marked all along the length of the tape so as to allow of ready adjustment at the beginning. The bands should be numbered as well as each of the direct and inverse keys.

The stations called for communication should be equipped with an identical set of strips, and these should be utilized according to any arbitrary system or order, and with variable datum points at start.

The system hereinbefore disclosed is adapted to code any desired text. All that is necessary is to key this text at the sending station, with the key strip travelling in normal manner, and to receive with the receiver apparatus while stopping the key strip of the receiver so as to have a series of dots and dashes having no relation with the open or clear text. To decode, a transmitter apparatus would be used to key the incoming signals after having placed the key strip in the same initial position as that when coding, that is to say, in the position in which the key strip of the receiver has been stopped.

Having thus described the nature of my invention, I claim:

1. In a system of secret telegraphy, a

manually operative key, an auxiliary key for enciphering the manually keyed signals, a perforated strip for automatically controlling said auxiliary key, an electromagnet connected to both said keys and controlled thereby for energizing a line circuit, and means including said electromagnet for feeding said perforated strip forward with each impulse sent through the line circuit.

2. In a system of secret telegraphy, a manually operative key and an auxiliary key for enciphering the manually keyed signals, a perforated tape for automatically controlling said auxiliary key, a relay connected to both said keys and controlled thereby for energizing a line circuit with impulses corresponding to the enciphered signals, and means including said relay for advancing said perforated tape a distance proportional to the number of impulses which comprise the individual signals, by a discontinuous movement corresponding to each impulse transmitted over the line circuit.

3. In a system of secret telegraphy, a manually operated key, an auxiliary key cooperating therewith, a perforated tape for automatically controlling said auxiliary key, and means controlled by both said keys for advancing said tape a distance proportional to the number of impulses which comprise the particular signal to be transmitted, by a discontinuous movement halted at the end of each impulse.

4. In a system of secret telegraphy, an auxiliary key and a perforated tape for actuating said key arranged at both the transmitting station and the receiving station, and means at each station for synchronously advancing both tapes through equal distances and a distance proportional to the number of impulses which comprise the individual signal transmitted, by a discontinuous movement halted at the end of each impulse with each transmitted current impulse.

5. In a system of secret telegraphy, the combination with a manually operated key, of an auxiliary key cooperating therewith to encipher the manually keyed signals, a perforated tape for automatically controlling said auxiliary key, means including an electromagnet controlled by both said keys for advancing the perforated tape a distance proportional to the movement of impulses which comprise the signal, by a discontinuous movement halted at the end of each impulse, and an armature actuated by said electromagnet for closing a line circuit to transmit the enciphered signals.

6. A system of secret telegraphy comprising a manually operated key and an auxiliary key cooperating therewith for enciphering the keyed signals, a perforated tape for automatically operating the auxiliary key, means associated with both said keys for transmitting impulses corresponding to the

enciphered signals, means for receiving the transmitted signals, a second pair of keys, one operated by the receiving means and the other by a perforated tape identical to the first mentioned tape, a relay controlled by both said last mentioned keys for recording the originally keyed or deciphered signals, and identical means associated with the transmitting means and with said relay for synchronously advancing both tapes a distance determinable by the number of impulses in the make-up of each individual character transmitted and with each transmitted impulse.

7. In a system of secret telegraphy where the characters are represented by a number of current impulses of different time duration, means for altering the normal code impulses of a character to be transmitted comprising a manually operative key, an auxiliary key, each of said keys having a stationary contact connected to a positive end of a source of energy and a second stationary contact connected to a negative end of said source of energy, a perforated tape for automatically operating said auxiliary key, an electromagnet connected to both said keys and adapted to be energized whenever said keys contact with contacts of opposite sign, an armature actuated by said electromagnet for energizing a line circuit and means including said electromagnet for feeding said perforated tape a length proportional to the number of impulses constituting a character by a discontinuous movement halted at the end of each individual impulse.

FRANCOIS CARTIER.
